JOSEPH R. ANGELOVICH, OF SAN FRANCISCO, CALIFORNIA, ASSIGNOR TO ANGELOVICH
IMPROVED HINGE COMPANY, OF SAN FRANCISCO, CALIFORNIA, A COPARTNERSHIP.

NON-PROJECTING HINGE.

1,076,259.

Specification of Letters Patent.

Patented Oct. 21, 1913.

Application filed January 14, 1913. Serial No. 742,070.

To all whom it may concern:

Be it known that I, JOSEPH R. ANGELOVICH, a citizen of the United States, residing at San Francisco, in the county of San Francisco and State of California, have invented new and useful Improvements in Non-Projecting Hinges, of which the following is a specification.

The object of the present invention is to 10 provide an improved hinge for hinging sewing machines, or other, tables, doors, box covers or other objects when it is desirable that the hinge should not project above the surfaces of the parts hinged together.

15 I have herein shown the invention as applied to the table of a sewing machine, but it will be readily understood that it may be equally well applied to other tables, doors, or other objects.

20 In the accompanying drawing, Figure 1 is a broken front view of a sewing machine table equipped with my improved hinge; Fig. 2 is an enlarged broken plan view of the same, extended; Fig. 3 is a sectional view of the same, extended; Fig. 4 is a similar view of the same closed; Fig. 5 is a sectional view on a still larger scale of the hinge in the extended position of the table; Fig. 6 is a detail sectional view.

25 Referring to the drawing, 1 indicates a table, and 2 an extension hinged thereto by my improved hinges. In recesses 3 in the vertical edge of the table are secured by screws 4 straps 5 of hinges, and the other

30 straps 6 thereof are secured, by screws 7, to the bottoms of recesses 8, formed in the upper surface of the extension 2 of the table. Each strap, except the bearing thereof, is concealed by a plate or block 9 of wood

35 fitting snugly within the corresponding recess. To said vertical edge is secured a molding 12, and the adjacent edge of the extension 2 is so formed that said molding supports said extension in a horizontal 40 position when extended. Said straps 5, 6, of each hinge are bent around at their ends to form bearings or eyes 13, in which are received the sides of a loop 14 by which the extension is hinged to the table. In order

45 to insure that the loop shall be horizontal when the extension is extended, the bearing or eye of the strap secured to said extension is formed with a curved projection 15, which, in the extended position of the extension, fits snugly beneath the eye of the other

strap. In the swinging of the extension upon its hinges, the projection 15 engages the rounded lower portion of the bearing of the other strap and causes the two bearings to assume the same horizontal level.

50 The outer surface of the movable bearing or eye 13 is not accurately cylindrical, for, if it were so made, the result would be that, in many cases, in swinging the extension 2 on its pivot, the loop 14 would not lie in the same plane as said extension. That is to say, said loop 14 would permit the extension to shift without turning, so that the extension 2 might not lie on the table 1 with its ends properly registering with the ends of 55 said table, but might be shifted longitudinally relatively thereto. In order to avoid this result, I enlarge the outer surface of the bearing 13 or shape it in the form of a cam as shown at 16, so that the bearing 13 of the extension 2 cannot turn on the loop 14 without said cam-shaped portion binding against the outer surface of the other bearing 13. In consequence of said binding, the movable bearing 13 rolls upon the fixed 60 bearing 13 when the extension is moved from its outermost position. But, when said extension has been turned through more than a right angle then said cam-shaped portion 16 enters a cavity 17 formed 65 in the outer surface of the fixed bearing 13, so that the extension 2 is properly centered upon the table 1.

70 It will readily be seen that with a hinge of this construction, the extension top, 75 when in its extended position, will lie perfectly level with the table top proper, and the hinge will not project above said level. The construction therefore is very advantageous for sewing machines or other tables, 80 in which it is desirable that light fabrics may be moved on said table without meeting with any obstruction. The hinge is also useful, whenever it is required that it should not project above the surfaces of the 85 objects connected by said hinge. It will also readily be seen that this improved hinge permits the extension to lie close against the upper surface of the table when in a closed position.

90 I claim:—

95 1. A non-projecting hinge for hinging together two objects such as a table and an extension thereof, comprising a strap in a recess in an edge of the table and secured to 100

said table and having an eye extending up to, but not above the surface of the table, and a strap secured to said extension having an eye extending to, but not above, the surface of the extension, and a loop having sides each engaging one of said eyes, one of said straps having a projection or finger arranged to engage the eye of the other strap to insure the parallelism of the loop with said surfaces when in the extended position.

2. A non-projecting hinge for hinging together two objects such as a table and an extension thereof, comprising a strap in a recess in an edge of the table and secured to said table and having an eye extending up to but not above the surface of the table, and a strap secured to said extension having

an eye extending to, but not above, the surface of the extension, and a loop having 20 sides each engaging one of said eyes, the extension strap-eye having an enlarged cam-shaped portion adapted to bind upon the other strap-eye when the extension is moved from its extended position, and said 25 other strap-eye having a cavity adapted to receive said cam-shaped portion when the extension is moved into its collapsed position.

In testimony whereof I have hereunto set 30 my hand in the presence of two subscribing witnesses.

JOSEPH R. ANGELOVICH.
